UNITED STATES PATENT OFFICE.

MAX E. VOIGT, OF NEW HAVEN, CONNECTICUT, ASSIGNOR TO THE ENGLISH & MERSICK CO., OF NEW HAVEN, CONNECTICUT, A CORPORATION.

LATCH FOR VEHICLE DOORS.

1,098,926.

Specification of Letters Patent.

Patented June 2, 1914.

Application filed March 27, 1914. Serial No. 827,537.

To all whom it may concern:

Be it known that I, MAX E. VOIGT, a citizen of the United States, residing at New Haven, in the county of New Haven and State of Connecticut, have invented a new and useful Improvement in Latches for Vehicle-Doors; and I do hereby declare the following, when taken in connection with the accompanying drawings, and the characters of reference marked thereon, to be a full, clear, and exact description of the same, and which said drawings constitute part of this application, and represent, in

Figure 1 a plan view of a latch for vehicle doors constructed in accordance with my invention, showing the latch bolt in its raised or disengaged position. Fig. 2 an end view of the latch. Fig. 3 a view similar to Fig. 1 with the cap removed and showing the latch bolt in its locked position. Fig. 4 a face view of the strike plate. Fig. 5 a top or edge view of the latch. Fig. 6 a sectional view showing the latch bolt engaged with the keeper.

This invention relates to an improvement in latches for vehicle doors, particularly for automobile doors where a firm engagement of the latch with its keeper is desired, the object being to provide a simple form of latch easily operated with the keeper co-acting with the latch bolt so as to practically lock the door in its closed position; and the invention consists in a latch having certain details of construction and combinations of parts as will be hereinafter described and particularly recited in the claims.

In carrying out my invention, I form the latch case from a back-plate 2 formed with a flange or end plate 3 through which the nose 4 of the latch bolt 5 extends. This latch bolt is mounted upon a hub or roll-back 6 which may be provided with a square opening 7 for the shank of a knob. The bolt is also formed with a rearwardly projecting tail 8 provided with a lug 9 adapted to be engaged by a lever 10 which is pivoted to the plate as at 11 and which projects upward through the upper edge of the door in the usual manner of vehicle latches. The nose of the bolt is normally depressed by a spring 12 and the bolt and spring with the lower end of the lever are inclosed by a cap or casing 13, preferably formed, like the plate 2, from sheet metal and secured thereto in the usual way.

The nose of the bolt which forms an important part of this invention is provided at its lower inner edge with a rounded surface 14 which co-acts with the keeper as a latch as will be hereinafter referred to. The forward edge of the bolt is provided with a locking flange 15 for the purpose as will hereinafter appear; and it may be stated that the opening 16 in the face plate corresponds mainly to the thickness of the bolt 5, but at its upper end is cut away to clear the upper surface of the nose of the bolt as well as the upper end of the flange 15 so that the bolt may be retired to the necessary point. In connection with a latch thus constructed, I employ a keeper 17 formed with a thickened front wall 18 which is cut away to form an inclined surface 19 opening into the upper portion 20 of the bolt-receiving slot the lower end 21 of which corresponds in width to the thickness of the main portion of the bolt 5. When the door is being closed it is unnecessary to turn the bolt either by the knob handle or by the lever 10 as the inclined surface 14 striking the cam 80 or inclined surface 19 will cause the bolt to move upward or be retired acting in the same way as the usual beveled nose of a latch. As the bolt rides up the inclined surface 19 it enters the upper portion of the slot 20 in the keeper, and then under the action of the spring 12 is depressed so as to pass into the contracted portion 21 with the inner wall of which the flange 15 engages as clearly shown in Fig. 6 of the drawings. 90 Consequently the door may be closed by mere pressure upon it as the latch rides up the incline and is retired; but when engaged, the latch bolt acts practically as a latch as it cannot by any possibility be disengaged 95 from the keeper without manually moving it either by the handle or by the lever. When it is desired to open the door, however, it is only necessary to move the lever to lift the nose out of the lower portion of 100 the slot 21 in the keeper when it can ride out of the upper portion 20. I thus provide at very low cost a simple latch for vehicle doors which permits the door to be closed in the same way as though it were provided 105 with an ordinary latch, and when closed it is as securely fastened as though locked with a bolt.

I claim:

1. A latch for vehicle doors comprising a 110

casing, a bolt mounted in the casing said bolt provided at its lower rear edge with a latch surface and at its forward edge with a locking flange, means for moving the bolt, 5 and a strike plate formed in its inner edge with a cam surface and with a slot into which the nose of the bolt may be entered, said slot contracted at its lower end and forming a wall with which the flange on the 10 bolt may engage.

2. A latch for vehicle doors comprising a casing formed with a front plate or flange having a bolt opening, a bolt mounted in the 15 said casing, a spring engaging with the bolt, and means for turning the bolt, the nose of the bolt formed at its outer lower corner with a rounded latch surface and at its inner edge

with an inwardly projecting locking flange, combined with a strike plate having an extension in its inner wall, said inner wall 20 formed with an inclined surface over which the nose of the bolt may ride, said strike plate formed with a slot to which the inclined surface extends, said slot contracted at its lower end forming a wall with which 25 the flange on the nose of the bolt may engage.

In testimony whereof, I have signed this specification in the presence of two subscribing witnesses.

MAX E. VOIGT.
